UNITED STATES PATENT OFFICE.

AIMÉ PILLON AND ETIENNE RAVAZ, OF OULLINS, FRANCE.

LIQUID AND LIKE TAP.

Application filed October 26, 1921. Serial No. 510,531.

To all whom it may concern:

Be it known that we, AIMÉ PILLON and ETIENNE RAVAZ, both French citizens, and residing in Oullins, Rhône, in the Republic 5 of France, have invented certain new and useful Improvements in or Relating to Liquid and like Taps, of which the following is a specification.

The tap forming the subject matter of the 10 present invention is of the kind having a definite feed and an automatic closure which comprises generally a piston valve closing communication between the inlet and outlet openings for the liquid by the 15 action of a spring and the pressure of the water which exists behind the piston. Communication is effected when the said piston valve is thrust by the hand and such communication is maintained for a period the 20 length of which is variable and depends on the size of a hole provided in the wall of the piston, such hole allowing of the passage of the water to the forward side of the piston in order to establish equilibrium 25 on the two faces of the piston and allowing of the spring acting on the piston which is automatically and gradually closed so as to interrupt or stop the escape of water.

The invention is characterized by the use 30 in combination with known parts of other members such as a valve with a grooved rod on which the piston valve is mounted, a cylindrical obturator with a hollow rod and a handle which are arranged in such 35 manner with the known parts so as to form a tap of extreme simplicity and construction and of certain action and which is capable of numerous and varied applications.

In order that the invention may be clearly 40 understood reference is made to the accompanying drawing which shows a constructional form of cock or tap in accordance with the present invention.

Figure 1 is a longitudinal axial section 45 showing the movable parts in the full open position and in closed position in dotted lines;

Figure 2 is a longitudinal axial section 50 showing the same parts, that is the movable parts, in the closed position;

Figure 3 shows the open position of the 55 valve mounted in the bucket piston valve.

The body R of the cock or tap is of cylindrical form and is provided with a tubular inlet a and a tubular outlet b for the liquid, these two tubular openings being

disposed at right angles to the axis of the cock or tap and in alignment with each other. The tubular inlet a is in communication with a cylindrical pressure chamber c, j situated at one end of the body R and in which is disposed a bucket piston valve h, g. The tubular outlet b communicates through an opening d with a cylindrical chamber e of smaller diameter than that of the chambers c, j of which it forms an extension and which ends at the other end of the body R or which may be closed by a screwed plug f. On the opposite side of the plug the outlet chambers e form in the interior of the pressure chamber c, j a seat e' for a closure valve rigid with the piston h.

The body R is closed at one end by a plug f and at the other end by a cover i screwed on to the cylindrical portion of the tap and which forms one of the walls of the chambers c, j; the other wall is formed by an annular partition arranged transversely of the cylinder and situated to the rear of the seat e'; this partition is provided with an opening c' which allows of connection between the chamber c, j and the tubular inlet a. The chamber of small diameter or the outlet chamber e is in communication with the tubular outlet b by the opening d formed in the wall of the body R of the tap.

In the outlet chamber is mounted with slight friction a hollow cylinder forming an obturator, l open at one end and closed at the other end by a disc which is provided with a number of holes k the said disc being provided with an extension formed by a tube m passing through the plug f. The plug f is provided with a stuffing gland formed by a leather washer x situated in an annular recess in the said plug, the said recess being closed by a washer y. The end of the tube m which extends through the plug f is closed and adapted to receive a handle n for manipulating the tap.

The bore of the tube m is adapted to serve as a guide for one end of a cylindrical rod q, the other end of which is recessed longitudinally so as to form grooves u extending into a collar t situated at a definite point in the length of the said rod, the said grooves extending to the screw threaded portion q' which is provided on the end of the rod. The grooved portion of the said rod is surrounded by a sleeve r the length of which is slightly less than that of the grooved portion of the rod; the sleeve is provided with

a collar r' having its forward face plain which face abuts against a leather or rubber washer g and is maintained against this face by a metallic washer and by two members h between which is secured a leather washer h forming the piston valve which is adapted to slide in the chamber c .

On the screwed end q' of the rod q is screwed a disc s between which and the end 10 of the rod q is disposed a leather or rubber washer s' , the said washer being applied against a shoulder formed by the difference in diameter between the screw threaded part q' and that of the grooved portion u . The 15 disc with its resilient washer forms a valve which is always subject to the tension of a helical spring v which bears at one end against the disc i and constantly forces the valve against its seat which is formed by the 20 end of the sleeve r .

The members h and h' forming the piston are provided with holes w which register so as to balance the pressure against the two faces of the piston and to permit of the liquid passing to the rear of the piston. The latter therefore divides the chamber into 25 two compartments. The rear compartment c , contains the valve h , and the forward compartment j contains the valve s, s' .

30 The action of the tap hereinbefore described and shown is as follows, starting from the position of the part shown in Figure 2. It will be seen at first that in the position shown in Figure 2, the bottom of the bore o of the tube m is at a certain distance from the end of the rod q , the said rod being forced into this position by the spring v which applies the closure disc l against the plug f . The obturator uncovers therefore 35 the outlet opening d but the liquid cannot enter therein since the chamber e is closed by the valve g which is applied against the seat e' by the action of the spring v acting on the valve s, s' and consequently on 40 the sleeve r which is rigidly connected with the valve g . It will be understood that the two compartments c and j being filled with the liquid the piston h, h' receives on one 45 face a pressure identical to that of the water, but it will be clearly understood that the forward face receives an additional pressure due to that of the spring v so that the piston is forced by the action of the spring in the direction of the chamber e , the inlet to the latter being therefore closed by the valve g 50 which is applied against the seat e' , Figure 2.

55 If sufficient pressure be exerted on the handle n so as to thrust the rod m and closure member l so as to compress the spring v , closure of the opening d by the cylinder l will at first be effected and finally the end of the rod q will abut against the plain bottom of the slide tube m .

60 On account of the large surface of the pis-

ton and the pressure existing in the compartment j the resistance offered by the forward face of the said piston is therefore very large, which resistance requires to be overcome by the manual manipulation of 70 the handle, but this force is sufficient to overcome the resistance offered by the small surface of the valve s and it follows that this valve is only thrust by the rods q, u and the sliding of the latter is therefore stopped 75 when the collar t abuts against the rear face of the sleeve r . This opening of the said valve s which is shown in Figure 3, uncovers the forward end of the sleeve r and the ends of the grooves u of the portion u' of the rod 80 q . The water enclosed in the compartment j escapes therefore through the grooves u so as to enter into the chamber e or the said water is obliged to remain stationary as soon as the outlet opening d is closed by the 85 obturator l . The reduced pressure therefore on the forward face of the piston gradually effects emptying of the compartment j but the valve g remains nevertheless applied on its seat e' as long as this pressure is 90 greater than that which is exerted on the rear face of the said piston.

95 When the pressure to which the forward face of the piston is subjected to less than the pressure exerted by the water entering by the tubular inlet a on the rear face of the piston, the latter is thrust forward by the pressure of a small quantity of this water only, but this pressure is sufficient nevertheless to move the valve g from its seat e' 100 so that the inlet to the chamber e is uncovered thus allowing the water to fill the said chamber but not to escape outside of the tube because the opening d remains closed as long as the slide tube is thrust into the 105 position indicated in dotted lines in Figure 1.

110 Whilst a part of the water fills the chamber e another part of the water passes by the grooves u in the piston rod and by the opening w in the piston so as to enter into the compartment j . Assuming that the surfaces of the forward face of the piston and the two faces of the valve s, s' are equal, the rear face of the said piston and the exterior face of the valve g and of the ring r' the piston valve h, h', g, r' and the valves s, s' are consequently in a state of equilibrium between the compartments c and j .

115 It follows that the resistance which would previously be opposed to the sliding of the piston under the pressure of the hand acting on the handle n no longer exists and the said piston can thus be thrust fully into the position shown in dotted lines in Figure 1 120 where it abuts against the cap or cover i . The handle n is consequently at the end of its stroke as well as the obturator l and its rod m as shown in dotted lines in Figure 1. 125 In this position of the parts the escape of 130

liquid is impossible since the obturator *l* closes the outlet orifice *d* and this escape only takes place when the manipulating handle is freed. The holes *k* which are formed in the disc at the rear of the hollow cylindrical portion *l* allow the water to pass in front of the said disc, the obturator thus being balanced and remaining stationary in its position. It follows therefrom that the parts *g*, *h*, *h'*, *s*, *s'*, *p*, *u*, *l* and *m* can remain an indefinite period in the position to which they have been thrust without the escape of any water being permitted.

In order that the water may escape, it is necessary that the handle and the rod *m* be forced to the end of its forward stroke in order that the obturator may be displaced in the same direction into the position shown in full lines in Figure 1 the piston valve *h*, *g* remaining stationary in the position shown in said figure. The chamber *e* is consequently open to the water issuing from the tubular inlet *a* and the opening *d* is uncovered by the obturator *l* so that the liquid can therefore escape by the said opening *d* and by the tubular outlet *b*.

A part of the water passes through the calibrated hole *w* formed in the piston and enters into the compartment *j* where the pressure becomes immediately equivalent to that existing in the compartment *c*. The valve *s*, *s'* is then subjected to the action of the spring *v* and is applied against its seat. The tension of this spring acts immediately on the piston so as to thrust it with a uniform speed which depends on the size of the hole *w*. The escape of the water is effected until the valve *g* is applied against its seat *e'* and closes the entry to the chamber *e*. A supply of water is therefore obtained during a definite time and automatic closure of the tube is effected. The supply can be suspended during any moment of the escape by exerting sufficient pressure on the rod *m* so that the obturator *l* closes the opening *d*. This closure, however, does not interrupt the feed of the water into the compartment *j* nor the action of the spring *v*. It follows that the valve *g* continues to be displaced and it is therefore applied against its seat without it being necessary to move the tube *m* rearwardly. In this case a rear thrust exerted on the handle effects the opening of the valve *s*, *s'* and the same effects take place as hereinbefore described.

For all pressures of the liquid the time necessary for the closure is directly proportional to the capacity of the forward chamber *j* and inversely proportional to the cross section of the escape opening *w*.

From the foregoing it follows that the water can be delivered to the tap by thrusting the obturator right to the bottom and thereafter withdrawing it.

A definite quantity of water in a definite time can thus be fed to the tube these two factors remaining always the same for the same pressure of the liquid and the same dimensions of the parts upon which the feed of liquid depends.

The forms and dimensions of the parts as well as the details may be varied in accordance with the various applications for which the tap is intended without departing from the scope of the invention.

Having now particularly described and ascertained the nature of our said invention and in what manner the same is to be performed, we declare that what we claim is:

1. In a valve for predetermined delivery of a fluid and automatic closure, a chamber for the passage of fluid, an inlet pipe and discharge pipe in communication with said chamber, a piston valve to close said chamber, a closing device provided with a handle to close the discharge opening, a hollow rod between said handle and the closing device, a rod slidable in the hollow rod of the closing device and connected with the piston valve which closes the first named chamber, and means for acting successively on the closing device and on the piston valve.

2. A body having an inlet, an outlet, a chamber between said inlet and outlet, and also having a pressure chamber, one end of said chamber being open and presented to said pressure chamber, and said chamber also having an opening in one side which communicates with the outlet; an obturator operable in the first named chamber to cover or uncover said opening, a piston valve movable in the pressure chamber and having a calibrated opening to balance the same therein, a rod movable by the obturator when the latter is moved to closed position, and on which said piston valve has limited movement, a valve of less diameter than the piston valve, movable therewith and arranged to seat against the open end of said first named chamber, said valve and said rod having coacting stops and said rod also having a channel to establish communication between the ends of the pressure chamber, and a spring actuated valve arranged on the front face of the piston valve and active to close said channel.

In witness whereof we affix our signatures.

AIME PILLOON.
ETIENNE RAVAZ.
